FAYE DE LASHMÉ, OF PALISADES PARK, NEW JERSEY

SIGNAL DEVICE

Application filed November 23, 1927. Serial No. 235,183.

This invention relates to signalling devices and more particularly is directed to a novel combination door-knocker and electrically operated bell, buzzer or indicator.

Door-knockers are highly prized as an artistic architectural embellishment but when actuated by a timid person or with insufficient force often fails to make known to the occupants of the house the presence 10 of the person manipulating the knocker. To overcome this and other objections, it is one object of the invention to provide a combination device of the character described of improved construction whereby 15 a bell, buzzer or indicator will be actuated on relatively slight movements of the handle of the door-knocker.

Another object of the invention is to provide an improved electrically operated bell, 20 buzzer or indicator, adapted to be readily installed to cooperate with existing door-knocking installations without altering or modifying the latter.

A further object of the invention is to 25 provide an installation of the character described which is rugged, adapted to withstand the roughest usage and may have electrically operated portions interconnected so as to be practically incapable of being put 30 out of order by the severest banging with the knocker handle.

Still another object of the invention is to provide devices of the character described comprising few and simple parts, which 35 shall be relatively cheap to manufacture and install, inconspicuous, and practical and efficient to a high degree in use.

Other objects of this invention will in part be obvious and in part hereinafter 40 pointed out.

The invention accordingly consists in the features of construction, combinations of elements and arrangement of parts which will be exemplified in the construction hereinafter described and of which the scope of application will be indicated in the following claims.

In the accompanying drawing, in which is shown various possible illustrative em- 50 bodiments of this invention,

Fig. 1 is a plan cross-sectional view of a door jamb and fragmentary portion of a door with an installation of an improved combination door-knocker and an electrically operated bell embodying the invention, 5t the bell, batteries and connecting wires being shown diagrammatically.

Figs. 2 and 3 are cross-sectional views taken on lines 2-2 and 3-3, respectively, in Fig. 1, and 60

Figs. 4 and 5 are plan and elevational cross-sectional views, respectively, of a modified construction of the invention, Fig. 4 corresponding to a section taken on lines 4-4 in Fig. 5. 65

Referring in detail to the drawing, 10 denotes a knocker secured in position on the exterior side of a door 11 in any well understood manner. The door 11 may be mounted for swinging against the jamb 12^a of a door frame 12 by means of suitable hinges 13. 70

The knocker 10 preferably is of artistic design and may be of any well known construction. As here shown said knocker comprises a striker or handle 14 formed with interconnecting arms 14^a, which are pivoted at their upper ends 14^b on a pin 16 supported by a lug 15^a of a backing piece 15. The backing piece 15 has a raised stud or anvil 15^b on its side facing the handle at the end opposite said lug for receiving the blows of a protuberating boss or weighted head 14^c of the handle. 75

The knocker 10 is actuated in the well known manner either by swinging the handle 14 and causing the head 14^c to beat against the anvil 15^b or by raising the handle and permitting it to fall by gravity so as to strike said head on the anvil. Frequently the knocker is actuated by a timid person who lightly taps therewith, or one who uses insufficient force to make known to the occupants in a remote place in the house the presence of the person knocking. It is one dominant purpose of the invention to provide means of novel construction to be simultaneously actuated on relatively slight displacement of the handle 14 from its lowered 80 85 90 95

or normal position of repose abutting the backing piece 15 as will hereinafter more fully appear.

This simultaneously actuated means may be electrically operated and if desired may be installed as a complete unit on the rear side of the door. As here shown said means comprise an electric switch 20 including a control plunger 20^a therefor, and conductor member 21 extending through a suitable recess 11^c of the door 11. Said members terminate in end contacts 21^b on the door, edge-surface 11^b as shown in Fig. 1. Spring control fingers 22 mounted in the jamb 12^a are provided to detachably connect with said contacts on swinging the door 11 shut to form a circuit with a signal apparatus, either of the indicating or alarm type, as for example, a bell 23 and lead wires 24, connecting with a suitable electric power source such as the battery 25 as shown in Fig. 1.

The recess 11^c is preferably bored to extend into the door from the edge surface 11^b and is circular in cross-section as shown in Figs. 2 and 3. Said recess is proportioned to snugly receive therein the conductor members 21 and switch 20 assembled as a unit structure by a stiff interposed bar 26 and interconnecting spaced bands 27. Said bar and bands contact with the walls of the recess and firmly retain the unit structure in the position as is clearly seen from Figs. 1 and 2. To prevent relative rotation of the switch in the recess the free exposed ends 21^b of the member 21 are fixedly secured against the door, edge-surface 11^b by screws 28.

For resiliently supporting the contacts 21^a for movement to and from each other the inner ends of portion 21^c carrying the contacts, are formed of spring material and may be made of insulated circular wires or ribbons.

The plunger 20^a which extends from recess 11^c through the door, has its inner end 20^b abutting one of portions 21^c of the members 21 so that when the exposed end 20^c of said plunger is forced in toward the door by pressure exerted on the handle in its normal position of repose, as shown at 29, due to gravity or the force of swinging the handle by a user, the contacts 21^a are separated and the switch 20 is opened. The slightest movement of the handle out of said normal position of repose releases the portion 21^c of member 21 permitting it to spring the contacts 21^a together and thereby closing the circuit through the switch 20.

The plunger 20^a is mounted to reciprocate through a bearing member 20^d and preferably is limited in its movement by providing stop nut 20^e, the outer free end 20^f of said plunger being fitted with an adjustable cap-nut 20^g having a locknut 20^h which is adapted to set the switch and the knocker-handle

in proper cooperating relation. The bearing member 20^d may be extended rearwardly as at 20ⁱ to form a support for the member portions 21^c as shown in Figs. 1 and 3 thereby facilitating the assembly and installation. 70

The operation of the improved door-knocking installation will now be apparent. With the door swung open as shown in Fig. 1, the electric system will be open circuited at the spring fingers 22. However, on closing the door the switch 20 will be connected in circuit as is readily understood. The handle 14 when swinging from its normal position of repose shown in full lines in Fig. 3 when lifted, relieves the plunger 20 from the force exerted by the weight of the handle pressing it in to the recess 11^c and permits the switch contacts 21^a to come together for closing the switch circuit thereby causing the bell 23 to ring. On releasing the handle and its return to its normal position of repose, the circuit will again be opened at the switch contacts 21^a and the bell ceases ringing.

In Figs. 4 and 5 a modified construction embodying the invention is shown. Here the knocker 110 may be similar to knocker 10 described above and shown in Figs. 1 and 3, inclusive, with the exception that the plunger 120 is slidingly mounted in a bearing member 120^a positioned above the upper pivoted end 114^b of the knocker handle 114. Said handle end 114^b is formed with a cam portion 114^c which abuts the cap nut 120^d of the plunger. Thus when the handle 114 is lifted from its normal position of repose for manipulating knocker, the plunger is pressed into the recess 11^c of the door 11 and carries the contacts 121^a on the resilient members 121 together completing the switch circuit. On return of the handle, the contacts 121^a are again separated as is clearly seen from Fig. 4.

It will thus be seen that there is provided devices in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A device of the kind described comprising a hinged door having a recess extending from the hinged edge of the door between the inner and outer sides thereof, a knocker having an anvil and a pivoted striker for bearing against the anvil mounted on the exterior side of the door, an elec-

trically operated signal device including a control switch extending into said recess, and a movable member under control of said knocker extending into said recess to control said switch.

5 2. A device of the kind described comprising a hinged door having a knocker on the exterior side thereof, said door having a recess between the sides thereof extending 10 from one edge of the door to a point behind said knocker, an electric signal device including a control switch comprising two elongated switch members extending within said recess normally out of engagement, and 15 a movable member under control of said knocker extending into said recess to control the engagement of said switch members.

In testimony whereof I affix my signature.
